UNITED STATES PATENT OFFICE.

GEORGE A. STANTON, OF PLACERVILLE, CALIFORNIA.

ORE CRUSHER AND PULVERIZER.

1,068,539.

Specification of Letters Patent.

Patented July 29, 1913.

Application filed April 23, 1913. Serial No. 763,120.

To all whom it may concern:

Be it known that I, GEORGE A. STANTON, a citizen of the United States, residing at Placerville, in the county of Eldorado and

- 5 State of California, have invented certain new and useful Improvements in Ore Crushers and Pulverizers, of which the following is a specification, reference being had to the accompanying drawings.
- 10 This invention relates to ore crushers and has for an object to provide an ore crusher which will crush and pulverize ores, novel means being provided for varying the space between the working faces of the confronting
- 15 rollers as desired.

A further object of the invention is to provide an extremely strong and rigid ore crusher which will be formed of a few simple parts that will not easily get out of order and may be manufactured at minimum cost.

With the above objects in view the invention consists of certain novel details of construction and combination of parts herein-
25 after fully described and claimed, it being understood that various modification may be made in the minor details of construction within the scope of the appended claims.

In the accompanying drawings illustrating this invention:—Figure 1 is a side elevation of the device. Fig. 2 is an end elevation of the device. Fig. 3 is a longitudinal sectional view on the line 3—3 Fig. 2. Fig. 4 is a cross sectional view on the line 35 4—4 Fig. 1. Fig. 5 is a fragmentary sectional view of the locking means.

Referring now to the drawings in which like characters of reference designate similar parts, 10 designates a pair of parallel bed sills. A pair of stationary upwardly and outwardly inclined castings 11 for journaling the crushing and pulverizing rollers on one side of the machine are secured to the sills, each casting having an attaching foot 45 12 which is rigidly secured to the related bed sill by bolts 13. A pair of posts 14 are secured to the outer faces of the castings 11, each post being fixed to the related casting by bolts 15 and rigidly braced against displacement by a knee 16 which conforms to the angle between the outer face of the post and the top face of the attaching plate, which knee is rigidly secured in place by the bolts 13 and 15 above mentioned. The 50 55 castings 11 are further rigidly braced by means of pairs of inclined braces 17, each

pair being secured at the lower ends to a related bed sill by a pin 18, and being secured at the upper ends to a related post by a pin 19.

Pivottally attached to the castings 11 and inclining oppositely therefrom are castings 20 for journaling the crushing and pulverizing rollers on the other side of the machine, these castings being adjustable with respect to the castings 11 within certain limits as will hereinafter appear, in order to vary the space between the coacting crushing and pulverizing rollers to adapt the machine to operate upon various ores. 60 A transverse shaft 21 is passed through suitable openings in the castings 20 and through hinge ears 22 on the castings 11 and forms a pivot for the castings 20. The castings 20 are provided each with an extension 23 which extends below said pivot and bears upon the outer face of the related bed sill for a purpose which will presently be described. A pair of posts 24 are secured to the outer faces of the castings 20 each post being rigidly fixed to the related casting by bolts 25 and being further fixed to the related extension 23 by means of bolts 26.

Formed in each extension 23 is an arcuate slot 27 having its center of curvature coinciding with the axis of the shaft 21, and through each slot and a suitable opening in the related bed sill a stop bolt 28 is passed. It is now clear that when the castings 20 are rocked in either direction on their pivot 80 shaft 21, the bolts 28 will contact with the ends of their respective slots 27 and thereby limit rocking movement of the castings 20, within which limits of movement the castings 20 may be adjusted to vary the space 95 between the rollers carried by these castings and the rollers carried by the stationary castings 11, to enable various ores to be most effectively operated upon.

Journalized at the ends in the stationary 100 castings 11 is a series of equally spaced apart superposed rollers substantially equal in diameter and in the present embodiment of the invention three in number as shown at 29, 30 and 31, although any preferred 105 number may be utilized without departing from the spirit of the invention. Journalized at the ends in the adjustable castings 20 is a series of superposed rollers 32, 33 and 34 which confront and coact with the related 110 rollers 29, 30 and 31 of the stationary casting in operating upon the ore. The upper-

most rollers 29 and 32 of both series are known as the first set of crushing rollers and these rollers are corrugated spirally longitudinally of their length, and are rotated toward each other, whereby a continual grind or crush of the ore is effected without clogging. The intermediate rollers 30 and 33 of both series are known as the second set of crushing rollers and these rollers are also corrugated spirally longitudinally of their length and are rotated toward each other, and it will be noted that by virtue of the divergency of the stationary castings 11 and adjustable castings 20, the second set of crushing rollers are disposed nearer together than the first set, whereby the ore which has been crushed by the first set into irregular fragments is crushed into still smaller fragments by the second set of rollers. The lower rollers 31 and 34 of both series are known as the pulverizing rollers and these rollers are rotated toward each other and have their cylindrical surfaces smooth, and by virtue of the divergency of the stationary and adjustable castings, the pulverizing rollers normally contact with a resultant pulverizing of the ore during its passage down between these rollers.

Any preferred means for actuating the series of rollers carried by each pair of the castings may be employed, but preferably the series of rollers are actuated by related trains of gears 35 and 36 which are driven by a common driving gear 37 carried by a stub shaft 38 which is journaled in a bracket 39 carried by one of the ground sills 10, which shaft in the present embodiment of the invention is illustrated as being driven by a sprocket gear 40, it being understood that any preferred driving means may be employed without departing from the spirit of the invention.

For adjusting the adjustable castings 20 and locking the same in adjusted positions, I provide a pair of links 41 which extend along the outer faces of the posts 14 and 24 near the upper ends of the latter, each link being pivotally connected at one end to the related end of the above mentioned pin 19 carried by the post 14 of the adjacent stationary casting 11, and having a longitudinal slot 42 near the opposite end which slidably receives a block 43 which carries a pin 44 that is secured to the related post 24 of the adjacent adjustable casting 20. A feed screw 45 carrying a hand wheel 46 is threaded through the end of the said link 41 and is engaged at the tip with the outer end face of the said block 42. Upon the feed screws being retracted, the weight of the adjustable castings 20 causes the castings to follow the feed screws with a resultant spacing apart of the crushing and pulverizing rollers to a greater extent than normal, and conversely upon advance of the feed screws

the adjustable castings will be rocked on their pivot toward the stationary castings with a resultant urging of the series of rollers carried by the adjustable castings toward the series of rollers carried by the stationary castings.

For locking the adjustable castings in various adjusted positions, I provide pairs of props 47 each pair being pivotally connected at the upper ends to the related pin 44 and being connected at the lower ends by a plate 48 which is engaged with a rack bar 49 carried on the top face of the related bed sill. The two pairs of props 47 are in the nature of strong rigid rods capable of withstanding the severe shocks and jars attendant upon the crushing and pulverizing of the ores during passage through the rollers.

A hopper 50 is secured to cap rails 51 and 52 which connect the tops of the posts 14 and 24 respectively, this hopper being designed to discharge its contents into the space between the first crushing rollers 32, the ore feeding down by gravity between the rollers to the second set of crushing rollers and from thence to the pulverizing rollers as ordinary. The hopper is braced on one side by inclined braces 53 that are connected to the posts 14 and is braced on the opposite side by vertical braces 54 that are connected to the bed sills 10.

For housing the rollers, both posts 24 are connected by end walls 55 and both posts 14 are connected by end walls 56. The posts 14 and 24 on each side of the machine are connected by side walls 57 and 58 respectively. The casing thus formed positively prevents escape of the ore until it has passed through the pulverizing rollers.

From the above description it will be seen that I have provided an extremely strong ore crushing and pulverizing machine, which machine may be adjusted within certain limits to operate upon various grades of ores, and furthermore that the device is formed of a few simple parts which will not easily get out of order.

What is claimed, is:—

1. An ore crusher including pairs of upwardly divergent bearing castings, coacting rollers carried by said castings, means anchoring one pair of said castings stationary, means mounting the other pair of said castings for limited pivotal movement relatively to said stationary castings whereby the angular relation of said pivotal castings relatively to said fixed castings may be varied, means for locking said pivotal castings in adjusted positions, and means for actuating said rollers.

2. An ore crusher including pairs of upwardly divergent bearing castings, superposed rollers carried by each pair of castings, a common support for both pairs of said castings, means rigidly anchoring one

- pair of said castings to said support, means pivots connecting the other pair of said castings to said stationary castings, interfitting means between said pivotal castings and said support limiting pivotal movement of said pivotal castings, manually controlled means for rocking said pivotal castings whereby to vary the angular relation between said pivotal castings and said stationary castings, and means for locking said pivotal castings in adjusted positions.
3. An ore crusher including bed sills, outwardly inclined bearing castings anchored stationary to said bed sills, rollers carried by said castings, movable bearing castings pivotally connected to said stationary bearing castings, means carried by said bed sills for limiting pivotal movement of said movable bearing castings, rollers carried by said movable bearing castings, means for adjusting said movable bearing castings whereby to vary the space between the rollers carried thereby and the rollers carried by said stationary castings, and means for locking said movable bearing castings in adjusted positions.
4. An ore crusher including pairs of upwardly divergent bearing castings, coacting rollers carried by said castings, bed sills supporting and rigidly connected to one pair of said bearing castings, a pivotal connection between the other pair of said castings and the first named pair of bearing castings, serving to permit of rocking of the pivoted castings toward and away from the stationary castings whereby to vary the space between said coacting rollers, means for rocking the pivoted castings on said pivotal connection, and means for locking said pivoted castings in adjusted position.
5. An ore crusher including bed sills, stationary outwardly inclined bearing castings carried by said bed sills, posts rigidly secured to said castings, inclined braces connected to said sills and to said posts and rigidly anchoring said castings in position, a series of superposed rollers journaled in said castings, movable bearing castings inclining oppositely from said stationary castings, pivotal connections between said stationary bearing castings and said movable bearing castings, a series of superposed rollers journaled in said movable bearing castings and coacting with the first named rollers in crushing and pulverizing ores, posts rigidly secured to said movable bearing castings, and inclined braces pivotally connected to said posts and adjustably con-
- nected to said sills, and serving to lock said movable bearing castings stationary in adjusted positions.
6. In an ore crusher, bed sills, upwardly and outwardly inclined stationary bearing castings carried by said sills, rollers carried by said castings, movable bearing castings inclining oppositely from said stationary bearing castings, rollers carried by said movable castings and coacting with the first named rollers, pivotal connections between said movable castings and said stationary castings disposed near the bases of said castings, a link connected to one of said stationary castings near the upper end thereof and extending across the space between said stationary casting and the related movable casting, said link having a slot therein, a block slidably fitted in said slot and operatively connected to said related movable casting, a feed screw carried by said link and terminally engaging said block, and serving to rock said movable castings toward and away from said stationary castings, and inclined braces connected to said block and adjustably connected to said sills for holding said movable castings in adjusted positions.
7. An ore crusher including bed sills, pairs of upwardly divergent bearing castings thereon, superposed rollers carried by each pair of castings, means rigidly anchoring one pair of said castings to said bed sills, pivotal connections between the other pair of said castings and said stationary castings, said pivotal castings each having an extension overlapping one side of the related bed sill below said pivotal connections, an arcuate slot in each extension having the radius of curvature coinciding with the axis of the related pivotal connection, a pin projecting through said slot and anchored to the related bed sill, and adapted to contact with the ends of said slot, whereby to limit pivotal movement of said pivotal castings, manually controlled means for rocking said pivotal castings whereby to vary the angular relation between said pivotal castings and said stationary castings and thereby vary the space between said coacting rollers, and means for locking said pivotal castings in adjusted positions.
- In testimony whereof I hereunto affix my signature in the presence of two witnesses.
